Primary Examiner — Lauren D McVey

(57) **CLAIM**

The ornamental design for a media processing device as shown and described.

DESCRIPTION

FIG. 1 is a first perspective view of a media processing device;

FIG. 2 is a second perspective view thereof;

FIG. 3 is a top side view thereof;

FIG. 4 is a bottom side view thereof;

FIG. 5 is a first side view thereof;

FIG. 6 is a second side view thereof;

FIG. 7 is a rear side view thereof; and,

FIG. 8 is a front side view thereof.

The broken lines immediately adjacent to the shaded areas depict the bounds of the claimed design, while all other broken lines are directed to environment. The broken lines form no part of the design claimed.

1 Claim, 8 Drawing Sheets
